UNITED STATES PATENT OFFICE.

ERNEST H. SHAFF, OF GRAND HAVEN, MICHIGAN, ASSIGNOR TO WILLIAM H. KELLER, INC., OF GRAND HAVEN, MICHIGAN, A CORPORATION OF MICHIGAN.

FLUID-PRESSURE-OPERATED TOOL.

Application filed May 10, 1920. Serial No. 330,017.

This invention relates to fluid-pressure-actuated tools, and refers more particularly, though not essentially, to tools of the percussion type commonly known as pneumatic hammers.

The objects of the invention are to produce a tool of novel and improved construction in which a working charge of motive fluid which moves the piston on its power stroke is separated into a primary and a secondary charge, the primary charge being utilized to continue the movement of the piston on its power stroke, and the secondary charge being utilized to return the piston; in which the entire control of motive fluid is effected by a single main control valve; and in which the efficiency of operation is greatly enhanced.

Further objects and advantages relating to details of construction will be pointed out in the following detailed description.

In the accompanying drawings Figure 1 is a longitudinal sectional view through a pneumatic hammer which is constructed in accordance with my invention. The section is taken in the plane of line 1—1 of Fig. 3.

Fig. 2 is an enlarged sectional view through the rear portion of the tool taken on the same plane as Fig. 1, but showing the main control valve in another position.

Fig. 3 is a transverse section in the plane of line 3—3 of Fig. 2.

Fig. 4 is a transverse section in the plane of line 4—4 of Fig. 1.

Fig. 5 is a longitudinal section through the tool taken in a plane indicated by line 5—5 of Fig. 3, which is substantially at right angles to the plane of Fig. 1.

Fig. 6 is an enlarged sectional view in the same plane as Fig. 5 showing the rear portion of the tool with the valve member in another position.

Figs. 7 and 8 are fragmental sectional detail views in the respective planes of lines 7 and 8 of Fig. 3, showing certain chambers and passages in the valve mechanism.

My invention is herein shown as applied to a pneumatic hammer of the type illustrated, described and claimed in my co-pending application Serial No. 371,445, filed April 5, 1920. It will be described in detail for the sake of clearness, but it should be understood that I do not intend to limit the invention to the present exemplary dis-

closure, but aim to cover in the appended claims all modifications and equivalents falling within the scope of my invention.

The tool shown in the drawings comprises an integral body or cylinder 10 having an internal piston chamber in which a solid piston 11 reciprocates. In the forward end of the cylinder is fitted the usual rivet set or analogous working tool 12 against which the piston strikes at the end of its working stroke.

At the rear end of the cylinder is the usual handle 13 having a tubular head 14 which may be mounted on the body in any preferred manner, as by means of screw threads, the handle being locked to the cylinder to prevent rotation of the handle by any suitable means including a pin 15 and a sleeve or ring 15^a. The handle has a supply passage 16 for live motive fluid, which passage is controlled by a manually operated throttle valve, the lever of which is designated 17.

Fitting within a counterbore at the rear end of the cylinder and partially enclosed by the head 14 of the handle is a tubular valve casing 18 which in the present instance is made of two interfitting sections. When the handle is turned up on its threads the valve casing sections are securely clamped in place, and held against rotation by a dowel pin 18^a.

A tubular valve member 19 fits slidably within the valve casing 18 and has a plurality of external annular flanges thereon forming shoulders or pressure areas against which the pressure of the motive fluid is exerted to move the valve member in opposite directions.

The handle head 14 provides an annular chamber 20 surrounding the rear end of the valve casing 18 and in constant communication with the supply passage 16 for the live motive fluid.

The rear end of the valve casing 18 is provided with inlet means 21, which may comprise an annular series of ports communicating with an internal annular groove in the valve casing, through which inlet means live motive fluid is introduced into the rear end of the piston chamber to move the piston on its forward or power stroke when the valve member 19 is in its forward position as shown in Figs. 1 and 5.

The valve 19 is held in such forward po-

sition by live air pressure in a small valve chamber 22 acting upon the small flange 23 on the valve member, the said chamber being in constant communication with the supply 5 of live motive fluid through a small port 24^a, (Fig. 7), communicating with the chamber 22 by means of a by-pass 24 clearly shown in Fig. 7. It will be obvious that at the beginning of the forward stroke the front end 10 of the by-pass 24 will be closed by the piston 11 and that after the piston 11 has passed the end of the by-pass it will also be in communication with the live motive fluid forcing the piston forward so that suitable pressure 15 against flange 23 will be maintained.

During the forward stroke the dead air in front of the piston exhausts as best shown in Fig. 5 through one or more passages 25 communicating with an annular chamber 25^a 20 back of the large flange 26 on the valve 19, from which chamber a duct or ducts 27 lead to the exhaust passages 28, which preferably open under a sleeve 15^a forming part of the locking means for the tubular head 14. Live 25 motive fluid will thus be supplied to force the piston forward and the dead air in front of the piston will be allowed to exhaust freely as long as the valve remains in the position illustrated in Figs. 1 and 5.

30 In its travel along the cylinder the piston uncovers the end of a passage 29 (Figs. 1 and 2) communicating with the annular chamber 30 in front of the large flange 26. The live motive fluid thereupon enters the passage 29 and fills the annular chamber as well as a plurality of storage passages 31 of which I have illustrated three. These storage passages communicate at their forward ends with the main cylinder, as shown, 35 but said ends are closed by the piston before the rush of live motive fluid into them from the other end has discharged any appreciable amount of air into the cylinder space in front of the piston. The live motive fluid 40 pressing against the front of the flange 26 overcomes the pressure on the small flange 23 and throws the valve back into the position illustrated in Figs. 2 and 6. During the first part of the movement of the valve the 45 pressure on flange 26 will be assisted by the pressure of the live motive fluid in the cylinder on the end surface 32 of the valve member, which has an area greater than that of flange 23.

50 If desired, a small auxiliary port or feeder 55 may be located in about the position indicated in Fig. 1 to start the discharge of live motive fluid into passage 29, chamber 30 and passages 31 a trifle before the open end of passage 29 is uncovered by the piston. A 60 moderate pressure may thus be built up in the chamber 30 and passage 29 before the piston uncovers the end of the passage so that the action of the valve when the passage 65 is uncovered will be more prompt.

The movement of the valve to the position illustrated in Figs. 2 and 6 cuts off the supply of live motive fluid from the annular chamber 20 to the cylinder and uncovers the annular chamber 34 which communicates directly with the exhaust passages 28. The main body of air in the cylinder is then allowed to exhaust quickly and approximately at the same instant as the impact of the piston against the tool 12. The movement of 70 the valve also operates to cover the ends of the ducts 27 with the edge of the large flange 26, enlarging the annular chamber 30 in front of the flange and putting it in communication with the passage 25 leading to the front end of the cylinder, as clearly shown in Fig. 6. The contents of the annular chamber 25^a pass out through duct 27 to the exhaust passages 28, said annular chamber being completely closed by the 75 movement of the valve.

Upon the recoil of the piston 11 from the tool 12, the live motive fluid stored in the passages 31 at the time the valve 19 was shifted to the return stroke position will now 80 flow through the annular chamber 30 and the passage 25 to the front end of the cylinder and force the piston 11 back on its return stroke. This pressure, however, will 85 obviously be much less than the line pressure and will decrease rapidly as the piston moves to the rear and allows the stored charge to expand. As soon as the front 90 ends of the storage passages 31 are uncovered on the return stroke, the stored air may enter the front part of the cylinder directly and substantial equilibrium of the pressure 95 of the expanding charge in the various passages will be immediately attained. On account of the rapid decrease in actuating pressure as the piston 11 moves back, the velocity 100 it will attain at the end of the return stroke will be very much less than that with which it struck the tool 12, thus diminishing the 105 recoil at the end of the return stroke.

110 During the major portion of the return stroke the by-pass 24 is in direct communication with the rear part of the cylinder which is exhausted practically to atmospheric 115 pressure by its direct communication with the exhaust passages 28. The small amount of live motive fluid entered through the port 24^a is therefore inadequate to build up any 120 pressure behind the flange 23. As soon, however, as the returning piston covers the front end of the by-pass 24, the pressure in the by-pass will immediately build up. Since the pressure in front of the large flange 26 is only that of the expanding 125 charge used to return the piston, which charge is by this time completely spent, the valve will be shifted forward by the pressure thus built up. By properly locating the front end of the by-pass 24 the shifting 130 of the valve may be made to occur just a

trifle before the piston 11 reaches the end of the return stroke so as to fill the end of the cylinder back of the piston with live motive fluid which receives and cushions the piston 11 and immediately throws it back on the next forward stroke.

It will thus be apparent that the returning piston is received against a cushion of air having the full line pressure and that if its momentum is sufficient it may pump a small amount of air back into the line while coming to rest, whereas if it were cushioned on a completely enclosed body of air the pressure might rise much higher than the line pressure producing a much more severe shock as the piston stops. It should also be noted that if a defective valve should tend to stick in its rearward position shown in Fig. 6, the piston will then be cushioned on completely enclosed air trapped at approximately atmospheric pressure when the end of the piston passes the annular chamber 34. This air upon being compressed by the piston will exert pressure on the end surface 35 of the valve and assist the pressure acting on the flange 23 in shifting the valve. In case of a serious defect resulting in complete jamming of the valve it should be noted that the piston will at all events be received on an air cushion so that it cannot strike a blow against the head casting, which would be likely to crack the same.

It will be seen that the tool I have provided contains no more parts than the tools of the prior art, but that I store part of the live motive fluid used to force the piston forward and deliver the same in front of the piston on the return stroke to move the piston back, instead of wasting an additional amount of live motive fluid, which would not only increase the consumption of live motive fluid but accelerate the piston 11 towards the end of its return stroke to an entirely unnecessary and undesirable speed. Furthermore, the pressure in front of the piston 11 at the end of the return stroke may in a properly designed tool be practically atmospheric so that the difference in pressure on the ends of the piston as it starts forward will be the maximum obtainable. If live motive fluid were used to return the piston, the passages for exhausting it could hardly be made adequate to bring the pressure in front of the piston to any such low value before the piston started back on the next stroke.

I claim as my invention:

1. In a fluid-pressure-actuated tool, a cylinder, a reciprocatory piston, a valve for controlling the movements of the piston, passages communicating with said cylinder adjacent its ends for delivering fluid to and receiving fluid from the same, and additional passages communicating with the cylinder at other points and arranged to be

controlled by said valve for storing pressure-fluid during the forward stroke of the piston, said additional passages being adapted to liberate the stored charge during the return stroke of the piston to actuate the piston on said return stroke.

2. In a pressure-fluid-actuated tool, a cylinder, a reciprocatory piston, a control valve, a control passage uncovered by said piston near the end of the forward stroke to deliver pressure-fluid to shift said valve, storage passages receiving a charge of live motive fluid through said control passage at the time of shifting of the valve, said storage passages being placed by said valve in communication with the front end of the cylinder whereby the stored charge acts to move the piston on the return stroke.

3. In a fluid pressure actuated tool, a cylinder, a reciprocatory piston, a passage communicating with the front end of the cylinder, storage passages communicating with the cylinder adjacent the front end and a control passage communicating with the cylinder at a point uncovered by said piston near the front end of the stroke, a valve member adjacent the rear end of the cylinder having chambers in communication with all said passages and acting upon receipt of pressure fluid from said control passage to fill said storage passages with pressure fluid and then to connect them with the passage leading to the front end of the cylinder, at the same time disconnecting the rear portion of the cylinder from the source of pressure fluid and connecting it to the exhaust ports.

4. In a fluid-pressure-actuated tool, a cylinder, a reciprocatory piston in said cylinder, a control valve adjacent the rear end of said cylinder and a plurality of passages controlled by said valve and communicating with said cylinder adjacent its front end, certain of said passages serving as exhaust means and other of said passages being controlled by said valve whereby to form storage means adapted to discharge into the front end of the cylinder to return the piston.

5. In a fluid-pressure-actuated tool, a cylinder, a reciprocatory piston in said cylinder, an annular control valve adjacent one end of said cylinder and adapted to control the flow of pressure fluid to and from the cylinder, a storage chamber having free communication with the cylinder adjacent the other end, and means carried by said annular valve for controlling the supply of fluid to said storage chamber.

6. In a fluid-pressure-actuated tool, a cylinder, a reciprocatory piston in said cylinder, a main control valve adjacent one end of said cylinder and adapted to control the flow of pressure fluid to and from the cylinder, an exhaust passage communicating with the other end of the cylinder and a storage

space independent of said exhaust passage controlled by said valve and also communicating with said cylinder adjacent its front end.

6. In a fluid-pressure-actuated tool, a cylinder, a reciprocatory piston in said cylinder, a control valve adjacent the rear end of said cylinder and a plurality of passages communicating with said cylinder adjacent its front end, certain of said passages serving as exhaust means and other passages serving as storage means, all said passages being controlled by said valve.

7. In a fluid-pressure-actuated tool, a cylinder, a reciprocatory piston in said cylinder, an annular control valve at the rear end of said cylinder, exhaust and supply passages for the rear end of said cylinder controlled by said valve, an exhaust passage for the front end of said cylinder controlled by said valve and a storage chamber for trapping a portion of live motive fluid on the forward stroke of the piston and delivering it in front of the piston on the return stroke, said storage chamber being controlled by said valve.

8. In a pressure-fluid-actuated tool, the combination of a cylinder and a reciprocatory piston in said cylinder, an annular control valve adjacent the rear end of said cylinder, exhaust ports arranged to be controlled by the extreme forward end of said valve, inlet ports arranged to be controlled by the extreme rear end of said valve, means providing a small annular pressure chamber for the valve, the rear edge of said valve providing an area exposed to the pressure developed in the rear end of the cylinder by the return of the piston, and means including a passage opening into the cylinder near its rear end so as to be controlled by the piston in such return movement for effecting a building up of live pressure in said pressure chamber, said passage being independent of the valve and opening into the cylinder forwardly thereof.

9. In a fluid-pressure-actuated tool, a cylinder, an annular control valve adjacent one end of said cylinder, a flange on said control valve defining annular chambers in front and behind said flange, four sets of passage-ways communicating with said chambers including an exhaust duct, a valve control passage, a storage passage, and a supply passage communicating with the extreme front end of the cylinder, said valve in one position connecting said supply passage with said exhaust duct and said control passage with said storage passage and in the other position connecting said storage passage with said supply passage and cutting off said control passage and said exhaust duct.

10. In a fluid-pressure-actuated tool, a one piece cylinder structure, a storage chamber in said cylinder structure communicating

with the cylinder adjacent its front end, and a control valve adjacent the rear end of the structure for filling said storage chamber with live fluid on the forward stroke and for connecting it to the extreme front end 70 of the cylinder on the return stroke.

11. In a fluid-pressure-actuated tool, a cylinder, a storage chamber opening freely into said cylinder adjacent the front end, an annular chamber at the rear end of said cylinder communicating with said storage chamber, and valve means in said annular chamber for automatically filling said storage chamber during the forward stroke of said piston, the front end of said storage 80 chamber being covered by the piston while the chamber is being filled.

12. In a fluid-pressure-actuated tool, a cylinder, a piston in said cylinder, a control passage uncovered by said piston toward the end 85 of the forward stroke, a storage passage opening freely into said cylinder, and means for filling said storage passage from said control passage while its front end is covered by the piston.

13. In a fluid-pressure-actuated tool, the combination of a cylinder, a piston, a valve having a small pressure chamber arranged so that in its rearmost position its rear end extends into proximity to the rear end of the cylinder but spaced therefrom, and means including a passage opening into the cylinder near its rear end so as to be controlled by the piston in its rearward movement for confining live pressure fluid in said chamber whereby to shift the valve member forward, said valve member providing in its rearmost position a closed pocket of substantial length in the rear end of the cylinder, said passage being independent of the valve and opening 100 into the cylinder forwardly thereof.

14. In a fluid-pressure-actuated tool, a one-piece cylinder structure having passages formed therein of three different kinds including a supply and exhaust passage communicating with the front end of the cylinder, a storage passage opening into the cylinder adjacent the front end, and a control passage opening into the cylinder at a point uncovered by the piston toward the end of the forward stroke, both of the last mentioned passages extending to the rear end of the cylinder structure.

15. In a fluid-pressure-actuated tool, a one-piece cylinder structure having passages formed therein of three different kinds including a supply and exhaust passage communicating with the front end of the cylinder, a storage passage opening into the cylinder adjacent the front end, and a control passage opening into the cylinder at a point uncovered by the piston toward the end of the forward stroke, both of the last mentioned passages extending to the rear end of the cylinder structure, said storage 115

110

120

125

130

passage being adapted to receive a charge of pressure fluid at its rear end from the rear end of said control passage and all of said passages opening directly and freely into 5 said cylinder.

17. In a fluid-pressure-actuated tool, a one-piece cylinder structure having passages formed therein of three different kinds including a supply and exhaust passage com-

10 municating with the front end of the cylinder, a storage passage opening into the cylinder adjacent the front end, and a control passage opening into the cylinder at a point uncovered by the piston toward the end of the 15 forward stroke, and a control valve operable upon delivery of pressure fluid to said control passage to fill the storage passage and then connect it to the supply passage.

18. In a fluid-pressure-actuated tool, a 20 cylinder, a piston in said cylinder, an imperforate annular valve adjacent the rear end of the cylinder, said valve having flanges defining annular passages and operating to control the movement of the piston, the 25 rearward movement of the valve operating to move the piston rearwardly, said rearward valve movement being limited by abutment of certain of said flanges with the cylinder leaving the rear edge of the flange exposed to the pressure in the rear end of the 30 cylinder.

19. In a fluid-pressure-actuated tool, the 35 combination of a main controlling valve and a storage chamber opening at its forward end into the cylinder and having at its rear end a connection with the rear piston chamber controlled by said valve.

20. In a pressure-fluid-actuated tool, the 40 combination of a piston, and means for controlling the movements of the piston including a storage chamber opening at its forward end into the forward end of the cylinder and having at its rear end a valve-controlled communication with the cylinder substantially centrally thereof.

21. A pressure-fluid-actuated tool having 45 a piston chamber, a valve member operable to control the flow of pressure fluid to and from the piston chamber to effect the reciprocation of the piston, and a storage chamber adapted to receive under the control of said valve member a charge of pressure fluid from the rear piston chamber and to discharge such pressure fluid into the forward piston chamber.

22. In a pressure-fluid-actuated tool, the

combination of a piston chamber, valve means including a large pressure chamber and a small pressure chamber, a storage chamber opening at its forward end into the forward piston chamber and communicating at its rear end with the large pressure chamber, means controlled by the valve for admitting pressure fluid from the rear piston chamber to said large pressure chamber, and means controlled by the piston in its rearward movement for shifting the valve member forwardly.

23. A pressure-fluid-actuated tool having a piston chamber, an annular valve at the rear end of said chamber adapted to receive said piston, means controlled by the piston for exerting a gradually decreasing pressure upon the larger pressure area of the valve to hold it in its rearward position including a storage chamber, said valve member being adapted when in its rearward position to form a closed pocket for the reception of the piston and having its rearmost end exposed to the action of the pressure fluid 80 compressed in said pocket by the piston.

24. A pressure-fluid-actuated tool having a piston chamber, a valve member forming in its rearward position a closed pocket adapted for the reception of the piston and having its rear end exposed to the action of the pressure fluid in the pocket, and means for exerting a gradually decreasing pressure upon the forward pressure area of the valve member as the piston approaches its rearward limit of movement, the last mentioned means comprising a passage opening at its forward end into the forward piston chamber and at its rear end opening into said pressure chamber.

25. A pressure-fluid-actuated tool having a piston chamber, valve means including a valve member, a large pressure chamber and a small pressure chamber, a passage opening at its forward end into the forward piston chamber and at its rear end into the large pressure chamber, means controlled by said valve member for admitting pressure from the rear piston chamber to the large pressure chamber, and means controlled by the piston as it approaches the rear end of the cylinder for effecting a building up of live pressure fluid in the smaller pressure chamber.

In testimony whereof, I have hereunto set 110 my hand.

ERNEST H. SHAFF.

CERTIFICATE OF CORRECTION.

Patent No. 1,645,166.

Granted October 11, 1927, to

ERNEST H. SHAFF.

It is hereby certified that error appears in the printed specification of the above numbered patent requiring correction as follows: Page 4, after line 118, claim 15, after the word "structure" and before the period insert a comma and the words ", and a valve between the control passage and the storage passage operable to trap in the storage passage pressure fluid admitted to the control passage from the cylinder"; and that the said Letters Patent should be read with this correction therein that the same may conform to the record of the case in the Patent Office.

Signed and sealed this 1st day of November, A. D. 1927.

Seal.
